UNITED STATES PATENT OFFICE

THOMAS J. McCORMICK AND ROBERT E. LINN, OF DETROIT, MICHIGAN; SAID LINN
ASSIGNOR TO SAID McCORMICK

DESIGN FOR A COMBINATION FENDER AND TIRE WELL

Application filed October 2, 1930. Serial No. 37,115. Term of patent 7 years.

To all whom it may concern:

Be it known that we, THOMAS J. McCORMICK and ROBERT E. LINN, citizens of the United States, residing at Detroit, in the county of Wayne and State of Michigan, have invented a new, original, and ornamental Design for Combination Fenders and Tire Wells, of which the following is a specification, reference being had to the accompanying drawing, forming part thereof.

Fig. 1 is a side elevation and

Fig. 2 is a top plan view of a combination fender and tire well showing our new design.

We claim:—

The ornamental design for a combination fender and tire well, as shown.

THOMAS J. McCORMICK.
ROBERT E. LINN.
